ATTORNEY

UNITED STATES PATENT OFFICE.

JACOB A. PEARCE, OF DENVER, COLORADO.

FOUNTAIN-BRUSH.

SPECIFICATION forming part of Letters Patent No. 380,345, dated April 3, 1888.

Application filed August 26, 1887. Serial No. 247,902. (No model.)

To all whom it may concern:

Be it known that I, JACOB A. PEARCE, a citizen of the United States, residing at Denver, in the county of Arapahoe and State of Colorado, have invented certain new and useful Improvements in Fountain-Brushes; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 My invention relates to that class of brushes which have reservoirs attached to them from which the brush is supplied with water.

The object of my invention is to provide a cheap yet strong and durable fountain-brush 20 for cleaning floors, windows, and the like, which may, when desired, be operated and adjusted to supply the scrubbing portion of the brush with water in such quantities as may be desired. I accomplish this object by the 25 mechanism illustrated in the accompanying drawings, in which—

Figure 1 is a front elevation of my device. Fig. 2 is an end view of the same.

Similar letters refer to similar parts throughout the several views.

In the drawings, *a* represents the reservoir, which is shaped as shown, and is provided with lugs *b* and a capped opening, *i*, on the top of the reservoir. The back of the brush *f* is of such a form as will admit the flexible pipe or hose *c* to be inlaid about one-half of its diameter along the front side, and provided with a longitudinal slot in its opposite side (indicated by dotted lines, Fig. 2) for the reception of the edge of a flexible strip, *m*, which strip is for the purpose of scraping or rubbing the floor or glass being operated upon. To the upper surface of the back are fixed by tacks or screws the lugs *g*, which are formed as shown and are provided with holes, through which the bolt *e* passes. This bolt is provided with a fixed head, *e'*, on one end, and on the opposite end is formed a screw-thread, on which the thumb-screw *d* operates 40 back and forth, and when brought in contact with the lug *g* adjacent to it the rod *e* is drawn toward the screw *d*, which clamps the lugs *g* against the lugs *b* on the reservoir and holds the brush in any position to which it may be 45 adjusted. The position when the scraper is

used is indicated by dotted lines, Fig. 2. I prefer to construct the tank of sheet metal, in which case the socket *h* for the handle *l* is soldered (at nearly right angles) to the back of the reservoir and is strengthened by the bracing-collar *h'*. The flexible hose *c* is passed over a short pipe, *c'*, (indicated by dotted lines, Fig. 1,) which surrounds an opening in the reservoir. The hose is then brought to the front of the brush back and inlaid, as before mentioned. Along this inlaid portion of the hose perforations are made, (marked *c*'), and this I prefer to hold in position by staples *j*, driven into the side of the brush's back. The cap *h* is made to closely fit a short pipe 70 surrounding an opening in the top of the reservoir, which pipe is marked *a'*, and is provided with an opening, *i'*, in one side, and the cap *h* is provided with a corresponding opening. This pipe and cap may be provided 75 with screw-threads to hold them together; or the cap may be held by friction.

In operating my device, to get proper results I remove the cap *h* and fill the reservoir with water, and at once place the cap in position, being sure that the opening in the cap does not come opposite the opening in the tube or pipe *a'*. When it is desired that the water be supplied to the brush *n*, the cap is turned to a point where the opening in the 85 cap comes opposite that in the pipe *a'*, when the air will pass into the reservoir and allow the water to flow out through the perforations *c*'' into the brush *n*. The scrubbing being completed, the water may be shut off by closing the opening on the top of the reservoir with the cap. The brush may then be turned to the position shown in dotted lines, Fig. 2, when the scraper or rubber *m* may be brought into action.

Having now fully described my invention, what I claim as new, and desire to secure by Letters Patent, is—

The combination of the reservoir, the brush adjustably pivoted to the bottom thereof, and the perforated flexible pipe connecting with the reservoir and extending along and secured to one side of the brush-block, substantially as shown and described.

In testimony whereof I affix my signature in presence of two witnesses.

JACOB A. PEARCE.

Witnesses:

R. M. McDERMOTT,
B. L. POLLOCK.
